POURING SPOUTS FOR LIQUID CONTAINERS

Carl Rasmussen, Bergen, Norway

Application November 12, 1952, Serial No. 319,945

Claims priority, application Norway November 12, 1951

5 Claims. (Cl. 222—538)

The present invention relates to liquid containers and more particularly to pouring spouts for such containers.

Sheet metal containers of the type generally used for oil and other liquids are commonly provided with a raised pouring neck to which it is known to attach a pouring spout to obtain better pouring facilities. Such pouring necks often have outwardly extending annular lips or flanges at their upper rims. When containers of this kind are delivered from the factory filled with liquid, they are usually sealed by a sheet metal seal over the pouring opening, a circumferential portion of such seal being crimped or folded around and under the lip or flange which is provided at the top of the neck for holding the seal in place. When it is desired to pour the liquid from the container, the seal is broken, and the pouring spout attached to the pouring neck. Such pouring spout must be sent, together with the container, being attached to the container with a temporary connection, for example a wire or string. It will be understood, however, that in such cases the pouring neck may easily become lost during shipment. It has also been proposed to provide the pouring neck with a permanently attached pouring spout. In practice, however, it has not been found possible to seal the neck of the container in the manner described above because, with the pouring spout permanently attached to the neck, the sealing tool does not have sufficient room to operate in applying the seal. Such containers must therefore be sealed in other ways which are less advantageous.

It is an object of the present invention to provide an improved pouring spout so that the pouring opening of the raised pouring neck may be sealed by means of a sheet metal seal crimped or folded over and around the top rim of the neck. In accordance with the invention, this is achieved by mounting the pouring spout on a collar which is substantially shorter than the neck of the container so as to be movable between a lower, or inoperative, position adjacent the top of the container and a raised, or operative, position adjacent the top of the neck. When the collar is in its inoperative position, the neck may be sealed in the above mentioned manner for shipment or storage. After such seal has been removed by the consumer, the collar carrying the pouring spout may be lifted to its operative pouring position and held in place on the pouring neck by the friction between the collar and the neck. Preferably, the pouring neck is made slightly conical with the walls diverging upwardly. By making the collar also conical, it will be held securely in its operative position simply by the friction between the collar and the neck and the resiliency of the sheet metals of which the neck and collar are formed.

A further characteristic feature of the invention is that the collar carrying the pouring spout is provided in its upper portion with an annular groove the cross section of which corresponds with the cross section of an outwardly projecting lip or flange provided at the top of the neck. When the collar is in its raised position, the rim of the neck seats in the annular groove so that the pouring spout is positioned substantially even with the top of the rim.

The nature and advantages of the invention will be more fully understood from the following description and claims in conjunction with the accompanying drawing, in which:

Fig. 1 is a perspective view of the top of a sheet metal

2

container with a pouring neck and a pouring spout in accordance with the invention.

Fig. 2 is a vertical section through the pouring neck and pouring spout, the former being sealed and the latter being in its inoperative position for shipment or storage.

Fig. 3 is a vertical section through the pouring neck and pouring spout, the seal being removed and the spout being in its operative position.

10 In the drawings, the reference numeral 1 indicates the top of a sheet metal container of the type usually employed for liquids. The container is provided with a raised pouring neck 2. The pouring neck is slightly conical, or tapered with its larger end up, and is soldered or otherwise permanently secured to the top 1 of the container. The walls of the pouring neck thus diverge in an upward direction. At the top of the neck, there is provided an outwardly projecting annular rim or flange 3 which is shown as a rolled edge. In the pouring opening, there is inserted a plug 4 as a temporary closure. The plug is shown as being formed of sheet metal and has an inturned rolled edge, frusto-conical side walls and a flat bottom. The pouring opening is sealed by a sheet metal seal 5 which is crimped or folded around and under the rim or lip 3 and removably covers the pouring opening of the neck 2, as shown in Figs. 1 and 2 of the drawings.

Around the pouring neck 2, there is provided a pouring member comprising a collar 6 and an outwardly extending pouring spout 8. The upper part of the collar is formed with an annular groove or recess 7 the cross section of which corresponds with the cross section of the annular flange or lip 3 of the neck. The collar 6 is slightly tapered or conical and its height is substantially less than the height of the neck, for example about half the height of the neck. The pouring spout 8 is substantially U-form or trough shaped in cross section and extends outwardly from the groove 7. It will be understood that the exact shape of the pouring spout member 6, 7, 8 may be modified and that this member is not limited to the specific shape shown by way of example in the drawing. The spout member is preferably stamped from sheet metal in a single piece and is placed around the pouring neck before the same is soldered or otherwise permanently secured to the container.

In Figs. 1 and 2, the pouring spout member is shown in its lower, or inoperative, position. In this position, there is enough room above the pouring spout member for the sealing tool to obtain a good grip around and under the annular lip or flange 3 during the sealing operation without being impeded by the pouring spout member. The pouring spout member remains in its inoperative position during storage and shipment of the filled container.

55 After the seal 5 and the temporary cap closure 4 have been removed by the consumer, the pouring spout member is raised to its operative position, shown in Fig. 3, whereby the collar surrounds the upper portion of the neck and the annular rim 3 of the neck seats in the annular groove 7 of the pouring spout member. The diameter of the collar 6 is such that, when the pouring spout member is in its raised position, the collar fits tightly on the neck so as to provide a fluid-tight joint and to hold the pouring spout member in place by the resiliency of the sheet metal parts and the friction between them. There is hence no need of other locking means for retaining the pouring spout member in its pouring, or operative, position. The closure 4 may be reinserted in the neck to close the container, for example after 70 part of the liquid has been poured out. The pouring member may be kept in its pouring position or, if desired, it can be returned to its inoperative position after each pouring operation.

In some instances, the annular groove 7 may be dispensed with and the pouring spout 8 extend directly out from the collar 6. This embodiment is, particularly but not exclusively, useful when the pouring neck either has no outwardly extending annular lip or flange 3 or only a very narrow flange. The pouring member will nevertheless be held securely in its operative position around the top of the pouring neck. It will be understood by

those skilled in the art that still other modifications may be made within the scope of the appended claims.

What I claim and desire to secure by Letters Patent is:

1. In a container having a top and a neck projecting up from said top, said neck being tapered with its larger end up and having an annular outwardly projecting lip at its upper end, a seal closing said neck and having its peripheral portion crimped over said lip to secure the seal in place, and a pouring member comprising a collar surrounding said neck and an outwardly projecting pouring spout, said collar having a substantially smaller axial length than said neck so as to be movable axially on said neck between a lower and an upper position and being of a diameter to fit tightly on the neck when the collar is in its upper position and the seal has been removed so as to be held firmly in place by friction. 15

2. In a container having a top and a neck projecting up from said top, said neck being tapered with its larger end up and having an annular outwardly projecting rim at its upper end, a closure member seating inside the neck, a seal overlying the upper end of the neck and having its peripheral portion crimped over said rim to secure the seal in place, and a pouring member comprising a collar surrounding the neck and a pouring spout extending outwardly from the collar, said collar having a substantially smaller axial length than the neck so as to be movable axially on the neck between a lower and an upper position and being of a diameter to fit tightly on the neck when the collar is in its upper position and the seal has been removed so as to be held tightly in place by friction. 30

3. In a container having a top and a neck projecting up from the top, said neck being tapered with its larger end up and having an annular outwardly projecting rim at its upper end, a seal overlying the upper end of the neck and having its peripheral portion crimped over said rim to secure the seal in place, and a pouring member comprising a collar surrounding the neck and a pouring spout extending outwardly from the collar, said collar being substantially shorter than said neck so as to be 40 movable on the neck between a lower and an upper position and being of a diameter to fit tightly on the neck when the collar is in its upper position and the seal is

removed so as to be held firmly in place by friction and said pouring member having in its upper portion an annular groove the cross section of which corresponds to the cross section of said rim so that the rim fits into said groove when the collar is in its upper position. 5

4. In a container having a top and a neck projecting up from the top, said neck having an annular outwardly projecting rim at its upper end, a seal overlying the upper end of the neck and having a peripheral marginal portion crimped over said rim to secure the seal in place, and a pouring member comprising a collar surrounding the neck and a pouring spout extending outwardly from the collar, said collar being substantially shorter than the neck so as to be movable on the neck between a lower and an upper position and being of a diameter to fit tightly on the neck when the collar is in its upper position and the seal is removed, and said pouring member having in its upper portion an annular groove the cross section of which corresponds to the cross section of said rim so that the rim fits into said groove when the collar is in its upper position. 20

5. In a container having a top and a neck projecting up from the top, said neck being tapered with the larger end up, a seal overlying and closing the upper end of the neck, and a pouring member comprising a tapered collar surrounding the neck and having its larger end up and a pouring spout extending out from the collar, said collar being substantially shorter than the neck and being movable axially on the neck from a lower position adjacent the top of the container and an upper position adjacent the upper end of the neck, the diameter of the collar being such that the collar fits tightly on the neck when in its upper position and the seal has been removed so as to be held firmly in place by friction. 35
